US0D1020653S

(12) **United States Design Patent** (10) **Patent No.:** **US D1,020,653 S**
(45) **Date of Patent:** **** Apr. 2, 2024**

(54) **LEVER FOR TERMINAL SOCKET**

(71) Applicants: **DINKLE ENTERPRISE CO., LTD.**,
New Taipei (TW); **DINKLE**
ELECTRIC MACHINERY (CHINA)
CO., LTD., Jiangsu (CN)

(72) Inventor: **Shang-Tsai Wu**, New Taipei (TW)

(73) Assignees: **DINKLE ENTERPRISE CO., LTD.**,
New Taipei (TW); **DINKLE**
ELECTRIC MACHINERY (CHINA)
CO., LTD., Jiangsu (CN)

(**) Term: **15 Years**

(21) Appl. No.: **29/816,992**

(22) Filed: **Nov. 27, 2021**

(51) **LOC (14) Cl.** **13-03**

(52) **U.S. Cl.**

USPC **D13/154**

(57) **CLAIM**

The ornamental design for a lever for terminal socket, as
shown and described.

DESCRIPTION

FIG. 1 is a perspective view of a lever for terminal socket
showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view thereof;

FIG. 9 is third perspective view thereof; and,

FIG. 10 is a perspective view showing the lever for terminal
socket in use.

The broken lines in the drawings illustrate both portions of
the article and environmental subject matter that form no
part of the claimed design.

1 Claim, 10 Drawing Sheets
